W. W. KEMP

METHOD FOR PRODUCING COMBUSTIBLE GAS

Filed Nov. 7, 1921

Inventor:
William Wallace Kemp,

By Edmund Bryant
Atty's.

UNITED STATES PATENT OFFICE.

WILLIAM WALLACE KEMP, OF BALTIMORE, MARYLAND.

METHOD FOR PRODUCING COMBUSTIBLE GAS.

Application filed November 7, 1921. Serial No. 513,444.

This invention relates to a new and improved method of producing gas, and has for its object to produce, continuously, combustible gases such as coal gas, water gas, hydro-carbon gases, or mixed coal and water gas.

In the production of coal gas under methods and with the apparatus now commonly in use, retorts are provided, which are externally fired and brought to a temperature which will carbonize the material contained in the retorts. Such methods require a large consumption of fuel, and the intense heat to which the retorts are subjected to bring the interior to a proper temperature to distill the coal tends to break the retorts down rapidly, and necessitates their frequent replacement.

The apparatus generally employed in the production of water gas, comprises a gas generator in which the fuel is placed, and this fuel is brought to incandescent, (as for example to a temperature of about 2000° F.) after which steam is passed through the incandescent mass and water gas generated. These alternate operations of bringing to incandescence and steaming generally result in waste, in that, during the heating up of the generator, the combustion gases and the heat produced pass out at the flue, so that under this method of producing water gas the gas yield from a given amount of fuel is very much reduced and the method is slow and intermittent.

By the method and apparatus which I have developed, and which will be described in detail hereinafter, a continuous production, either of coal gas, or water gas, or both, is maintained, and the refilling of retorts, such as are now used in the production of coal gas and the practice of externally firing, is done away with; while in the production of water gas, or mixed coal and water gas, the alternate heating and steaming steps with the consequent waste and slowness in production, is avoided.

I accomplish this result by providing a gas generator through which the fuel from which the gases are generated passes in a substantially continuous stream, or in an intermittent stream, and during such passage it is subjected, in a closed chamber, to the action of a self-sustaining flame which will bring it to the proper temperature for driving off the volatile products, and, furthermore, where water gas is to be generated, provision is made for steaming the heated

fuel without interruption of the heating action and without the necessity of alternating the burning and the steaming steps.

In order that the invention may be understood by those skilled in the art, I have shown, in the accompanying drawing, a gas generator embodying my invention, the drawing being a vertical longitudinal section.

Referring to the drawing by the numerals thereon, the gas generator is built up in any suitable manner, having the outer jacket 10, preferably of metal, with an insulation 10' adjacent the jacket, and the inner lining 11 of fire brick or other high heat resisting material.

The structure, composed of the elements 10, 10', and 11, forms a hollow gas generator having the central chamber 12 extending from the bottom to the top thereof, the top of the generator being covered by the hopper plate 12^a, surmounted by the hopper 13, provided, at its top, with an air-tight closure 14, and at its bottom with a sliding gate 15, so as to provide a trapped feed hopper for the chamber 12. It will be understood that the form of feed for the generator described is merely illustrative, and equivalent feeding means, such as a feed worm or other device may be substituted.

At a suitable point in the chamber 12 is provided a grate 16 of any suitable construction, and below that gate is a swinging gate or valve 17, operable from the outside of the generator by the handle 18, this valve or gate 17 closely fitting the chamber 12 so that the chamber will be substantially air-tight at the top and at the bottom, there being provided an ash pit door 19 to tightly close the opening 20 at the base of the generator, through which the burned products passing through the grate 16 and dumped by the valve 17 may be removed. There may be provided, of course, a conveyor of any approved type, as, for example, a screw conveyor at the bottom of the generator to remove the coke when coal gas is generated, or the ash, when water gas is formed.

It will be seen that there is provided, by this construction, a closed gas generator into which the fuel (for example, coal, wood, lignite, oil-shale, mineral oil, crude petroleum, or other gas producing material,) from which the gas is generated, is fed, and this loading of the generator may be con-

tinuous without admitting air, for the hopper 13, (or equivalent feeding means) is provided with the air-tight closure 14 and the gate 15, will admit charges of coal, or 5 other material under treatment, to the chamber 12 without allowing the entrance of air to that chamber, the lower part of the chamber being, of course, closed by the gate 17 and the closure 19, or equivalent means.

10 In order to bring the material passing down the generator to incandescence and release the gaseous constituents, there is provided a series of water-jacketed burners 21 having water jackets 21^a, arranged in any 15 suitable manner, but preferably, as shown, in circumferential series spaced apart vertically relative to one another. These burners project outwardly and radially through the wall of the generator to feeder tubes or rings 20 22, embedded in the wall and connecting at any suitable point in their circumference with the main feed pipe 23. The burners 21 deliver, under pressure, to the chamber 12 a mixture of fuel, preferably gaseous, which 25 is self-sustaining, such fuel having an air content sufficient to merely sustain combustion of the fuel issuing from the burners 21. That is, the amount of oxygen contained in the gaseous mixture supplied to the burners 30 is not in excess of that required to effect combustion of the fuel of that mixture. Such a mixture may be produced by any suitable means, for example, such as that of the patent to Kemp and Van Horn No. 35 1,420,658, dated July 27, 1922.

The mixture, such as produced by the apparatus of the Kemp and Van Horn patent, is a very thorough mixture, the air and gas constituents thereof being thoroughly intermingled, or mixed without stratification. 40 As a result of using such a thorough mixture, produced outside the generator, and the proportions being such that the oxygen therein does not exceed that required to 45 effect combustion of the gas in the mixture, the flame is maintained close to the face of each burner. This is a feature of considerable importance in carrying out my improved method. If the flame was permitted 50 to blow off from the face of the burner, some combustion of the gas making material or of the gas evolved therefrom will occur. However, by employing a thorough mixture of the particular nature referred to, which is 55 produced outside the gas generator, I insure that the flame will be maintained close to the face of each burner and avoid any combustion of the gas producing material, or gases evolved therefrom.

60 The term "combustion" is herein used as meaning the oxidation of a substance with the generation of heat. The burner tubes are inclined downwardly, and the ends of the orifices of the burners 21 are preferably 65 bell-mouthed, as shown, in order to prevent

any choking or clogging of the burner openings and tubes by the solid fuel in the gas generating chamber.

It will be observed that since air is not present in the chamber 12, the self-sustaining flame delivered from the burners 21 cannot set up active combustion of the coal or other material, since, in the absence of sufficient air to promote combustion, the coal will simply be heated to incandescence and 75 the volatile elements driven off, which volatile elements will pass out through any suitable delivery outlet, as pipe 24, at the top of the gas generator to any suitable scrubbing, or other apparatus, for further treatment. 80 The flame of the mixture supplied to the burners 21 will not therefore effect combustion of the coal or of the volatile elements released therefrom. As the distillation of the coal progresses it will be gradually coked 85 as it approaches the grate 16, and will pass through the grate and be dumped by the valve or gate 17 to the ash pit.

In order that water gas, or mixed water and coal gas, may be produced when desired, 90 I provide the chamber 12, preferably below the grate 16, with a steam coil 25 having a feeder 26, through which steam may be delivered, as desired, and driven up through the incandescent mass in the chamber 12 to 95 form water gas, or to combine with the volatile products from the coal and produce coal and water gas.

The advantages of the present method and the apparatus described for carrying it out, 100 are, that a continuous process is provided. After the burners are once lighted and the chamber is filled, a continuous generation, either of coal, or of water gas, or both, may be carried on. Another advantage is that 105 production may be very accurately regulated and the apparatus controlled, for the burners may be very accurately regulated as to the supply of self-sustaining fuel passing through them to the stack so as to ensure 110 proper control of the temperature, and a very complete distillation of the coal secured. Where water gas is produced there may be such regulation of the burners and of the steam supply as to maintain continuous 115 production, and eliminate the alternating method of blowing and steaming now in use. Furthermore, the method and the apparatus are such that a very material reduction in the amount of fuel used results, 120 for the alternate heating up and waste of gas and the steaming are eliminated, and the method proceeds continuously after firing 125 has begun.

It will be observed that atmospheric air 12 is effectually excluded from the chamber 12, both by reason of the closed character of the chamber which prevents ingress of any substantial volume of air, and, furthermore, the pressure generated within the 13

chamber by the incoming jets of self-sustaining fluid is sufficient to effectually resist atmospheric pressure and entrance of air.

Such changes in structure and variations 5 in the steps of the method from this disclosure as are within the skill of a mechanic, and obvious equivalents may be made and still be within the range of my invention.

I claim:

10 1. The method of producing combustible gas from material capable of evolving gas under the action of heat, which consists in charging the gas producing material into a gas generator, preventing the ingress of 15 air into said generator, and heating the material to form gas therefrom by projecting into the generator the flame produced by the combustion of a thoroughly premixed gas and air mixture, the amount of oxygen in 20 which is not in excess of that required to effect combustion of the mixture and is insufficient to produce combustion of the material.

2. The method of producing combustible gas from material capable of evolving gas 25 under the action of heat, which consists in charging the gas producing material into a gas generator, preventing the ingress of air into the generator, and heating the material to form gas therefrom by projecting into 30 the generator a plurality of circumferentially separated and vertically spaced flames produced by the combustion of a thoroughly premixed gas and air mixture, the amount of oxygen in which does not exceed that required to effect combustion of the mixture 35 and which is insufficient to effect combustion of the material or of the gas evolved therefrom.

3. The herein described process of producing combustible gas, which consists in charging gas producing material into a gasification chamber, and heating the material to form a combustible gas by subjecting it to the direct action of the flame and products 45 of combustion produced by burning within the gasification chamber a thoroughly premixed gas and air mixture, the amount of oxygen in which does not exceed that required for combustion of the mixture, without setting up combustion of the residue 50 produced or of the gas evolved.

4. The method of producing combustible gas including a portion of water gas, which consists in charging into a gas generator 55 material capable of evolving gas under the action of heat, preventing the ingress of air into said generator, heating the material to

form gas therefrom by projecting into the generator the flame of a burning thoroughly premixed gas and air mixture, the amount of oxygen in which does not exceed that required to effect combustion of the mixture, and which is insufficient to effect combustion of the material or the gas evolved therefrom, and passing steam through the mass of heated material to produce water gas.

5. The method of producing combustible gas including a portion of water gas which consists in charging into a gas generator 70 material capable of evolving gas under the action of heat, heating such material to form gas therefrom at a plurality of vertically spaced points by the heat of flames of a thoroughly premixed gas and air mixture 75 injected into the generator and the amount of oxygen in which does not exceed that required to effect combustion of the mixture and is insufficient to effect combustion of the gas producing material or the gas evolved 80 therefrom, while excluding from the generator air sufficient to cause combustion of the material or gases evolved therefrom, and injecting steam into the generator below the zone of material heated by the lowest flame 85 to produce water gas.

6. The method of producing mixed coal and water gas, which consists in charging coal into a gas generator, firing the coal in the generator internally by combustion of a 90 premixed gas and air mixture without setting up active combustion of the coal or the coal gas distilled therefrom, and admitting steam to the interior of the generator and thereby producing water gas.

7. The method of producing mixed coal gas and water gas, which consists in continuously charging coal into a container, forming gas from coal by burning within the container a thoroughly premixed gas 100 and air mixture, formed outside the container and the amount of oxygen in which does not exceed that required for combustion of the gas of the mixture, whereby it will not effect combustion of the coal, admitting steam into the resulting coke, thereby producing water gas, while maintaining the temperature of the coke by burning the thorough gas and air mixture, and removing the ash from the container.

In testimony whereof I have hereunto set my hand.

WILLIAM WALLACE KEMP.
